UNITED STATES PATENT OFFICE.

JOHN JOSEPH GAFFNEY, OF NEW HAVEN, CONNECTICUT, ASSIGNOR TO NATIONAL FOLDING BOX COMPANY, OF NEW HAVEN, CONNECTICUT, A CORPORATION OF NEW JERSEY.

COUNTER-DISPLAY FOLDING BOX.

Application filed November 19, 1921. Serial No. 516,306.

To all whom it may concern:

Be it known that I, JOHN JOSEPH GAFFNEY, a citizen of the United States, residing in the city of New Haven, in the State of Connecticut, have invented certain new and useful Improvements in Counter-Display Folding Boxes, of which the following is a specification.

My invention relates to that class of folding, usually paper, boxes, or containers, supplied with means, usually therewith integral and called "easel braces," for supporting them, as upon a merchant's counter, in inclined positions, thereby facilitating display of their contents to customers. The objects of my invention comprise supplying such easel braces from less material, more easily constructed and manipulated for use, and less conspicuous and more stable than here-
tofore.

I attain these and other useful objects by constructing the braces, and connecting them with the boxes, as follows, reference being had to the accompanying drawings, in which

Figure 1 is a plan of a cut-out and creased paper blank embodying my invention, some irrelevant parts being broken away.

Figure 2 is a perspective view of one end of a box set up from said blank (irrelevant parts being broken away), and showing my novel easel brace in operative position;

Figure 3 is, on enlarged scale, a central vertical sectional view taken on the line 3—3 of Figure 2, and viewed in the direction of the arrow;

Figure 4 is a similar view of the parts shown in Figure 3, my easel brace being collapsed into comparatively inoperative position.

The blank, preferably integral, is shown in Figure 1, cut out of paper, or other suitable, material in any preferred form, for example that shown in Figure 1, and the material is, where indicated by triple lines, creased, or otherwise relatively weakened, to promote its there bending or folding,—these operations being well known.

The well known type of box to which my easel brace is shown applied in the drawings comprises a bottom portion, 5, connected by creased portions, 5', 5', with the sides, 6, 6, and, by a creased portion 5'', with one end, 7, of the box. The sides carry, at one end,

usual types of flaps, 8. The end 7 carries 55 a well known extension, 9, carrying flaps, 9', 9' and 9'', the manner of inter-folding which with the extensions, 8, of the sides, 6, to hold that end of the blank in its "set up" position for box use, is believed to be too 60 well understood for further explanation.

The opposite ends of the sides 6 are, in this instance, provided with familiar tongues 10, 10.

Up to this point my invention is not in- 65 volved.

I provide the bottom 5 with a therewith bendably connected, composite, easel-forming extension, comprising a leg member, 11, connected with the bottom 5 along a prefer- 70 ably creased, or otherwise weakened, line, 5''. The leg 11 is, at its bottom or foot, similarly bendably connected with the bottom or foot of another thereto correspond- 75 ing leg member, 12, which is, in turn, sim- 75ilarly bendably connected with a member 7'', adapted to serve as the end of the box opposite to that designated 7, and provided with means, in this instance slots 13—13, with which the tongues 10, 10 cooperate in 80 upholding the set-up blank for box use. The folding connection between the legs 11, 12, may be a single creased, or otherwise weak- 85 ened, line of the constituent material, but I preferentially connect the legs with each other 85 by thereto additional, in this instance therewith integral, members 14, 14', respectively connected with 11 and 12 by the intermediate creased material at *a* and *b*, and with each other along the intervening folding line 90 15. If desired, the end 7'' may bendably carry an extension, 16, which may be shaped and proportioned to form a cover for the box, or a display flap, etc. etc.

From the foregoing I believe that the op- 95 eration of my box and of my easel brace will be readily understood. The end 7 and its above described therewith coacting parts having been bent, set-up, and interconnected as usual, the leg 11 is bent downwardly away from the bottom, and the leg 12 upwardly toward the bottom until the end piece 7'' is in position to serve as such, after which the tongues 10 are inserted into the slots 13, thereby firmly securing 7'' to serve as 100 one end of the box. This leaves the legs 11, 12, outwardly projecting as shown in Figs. 2 and 3 to serve as easel supports for the 105

box in its inclined, or display position. The intervening members 14, 14' enable the feet of the legs to be spread apart without collapsing; and the construction is such that whenever desired the legs may be folded together and bent back underneath the bottom of the box as indicated in Fig. 4, thus economizing space in storage when my inclined display is not needed.

Having now described my invention, what I claim as new and desire to secure by Letters Patent is the following, viz:

1. A counter-display folding paper box comprising a bottom and an end having normally substantially mutually contacting external edges each provided with a therewith integral therefrom projecting angularly thereto bendable leg extension, the said extensions having the bottoms or feet thereof connected with each other by bendable means.

2. A counter-display folding paper box comprising a bottom and an end having normally substantially mutually contacting external edges each provided with a there-

with integral therefrom projecting angularly thereto bendable leg extension, the said extensions having the bottoms or feet thereof bendably connected with each other.

3. A counter-display folding paper box 30 comprising a bottom and an end having normally substantially mutually contacting external edges each provided with a therewith integral therefrom projecting angularly thereto bendable leg extension, the said 35 extensions having the bottoms or feet thereof bendably connected with each other by a thereto additional therewith integral member.

4. A counter-display folding paper box 40 comprising a bottom and an end having normally substantially mutually contacting external edges each provided with a therewith integral therefrom projecting angularly thereto bendable leg extension, the said 45 extensions having the bottoms or feet thereof bendably connected with each other by a thereto additional therewith integral member having an intervening folding line.

JOHN JOSEPH GAFFNEY.
